ELECTRIC TOASTER

Donald William Morphy, Chislehurst, and William Morris Russell, Slough, England, assignors to Morphy-Richards Limited, St. Mary Cray, England, a company of Great Britain

Application December 5, 1949, Serial No. 131,226
In Great Britain December 7, 1948

10 Claims. (Cl. 99—329)

1

This invention relates to electric toasters of the kind comprising means whereby lowering of a bread-carrier into the toasting position within a toasting chamber engages a latch against the action of a loading spring and closes a main switch to establish the power supply circuit for one or more toasting elements, and automatic timing mechanism comprising a bimetallic strip having an associated subsidiary heating element energised from the power supply circuit, the bimetallic strip, after a predetermined flexure in one direction operating a subsidiary switch to deenergise the subsidiary heating element whereupon the bimetallic strip, on cooling, returns to a position wherein it trips the latch thereby permitting the carrier to rise under the action of the loading spring and reopen the main switch to render the toaster inoperative. Thus, each timing cycle comprises a heating stage terminated when the bimetallic strip operates the subsidiary switch, followed by a cooling stage terminated when the bimetallic strip has returned to the automatic tripping position, that is to say when the temperature of the strip has fallen to the automatic tripping value.

In toasters of this kind, the duration of each toasting period is usually preset by the operator who is then committed to the resulting degree of toasting so that under-toasted or over-toasted slices delivered at the end of the toasting period may be wasted until the operator has, by trial and error, found the correct time setting. If, as in some instances, a manually operated trip device is provided so that the operator can trip the mechanism during an automatic timing cycle, recharging of the toaster is then liable to result in the residue of the previous or interrupted toasting period being continued until the next automatic trip occurs, thus delivering only partly toasted bread. The main object of the invention is to meet this difficulty.

An electric toaster according to the invention is provided with manually-operable tripping mechanism, and locking means whereby, after manual tripping, the toaster, even if relatched, can again be rendered operative only when the temperature of the bimetallic strip does not exceed the automatic tripping value.

The invention may be carried into practice in various ways but one practical embodiment thereof is shown by way of example in the accompanying drawings, in which

Figure 1 shows the toaster in section on the line I—I of Figure 2,

Figure 2 is a section on the line II—II of Figure 1,

2

Figure 3 is a section on the line III—III of Figure 1,

Figure 4 illustrates, in elevation, the left-hand end wall of the interior frame included in Figure 1,

Figure 5 is a similar view of the right-hand end wall of the frame,

Figure 6 shows the timing mechanism on an enlarged scale and as viewed from right to left of Figure 1, with the hood removed,

Figure 7 is a plan of Figure 6,

Figure 8 is a view from left to right of Figure 6,

Figure 9 is a view from right to left of Figure 6,

Figures 10 and 11 are views similar to that of Figure 9 but with parts cut away and the elements in different operative positions,

Figure 12 diagrammatically represents the electrical circuit of the toaster, and

Figure 13 is a bottom plan view of the toaster.

In the construction shown in the drawings, the toaster comprises a metal frame having two plate-like vertical end walls, 1, 2 secured at their lower ends to two foot-strips 3, and at their upper ends to two longitudinal side strips 4 and two intermediate ties 5, 6. The side strips 4 and intermediate ties 5, 6 are mutually parallel and horizontally spaced apart with the two intermediate ties 5, 6 lying somewhat nearer to each other than to the side strips 4, as shown in Figure 3.

Each tie 5, 6 and side strip 4 is provided with two elongated slots 7 longitudinally spaced apart in the strip and in which engage two tongues 8 at the upper edge of a metal reflector plate 9 having a plurality of vertical flutes or ribs 10 indented therein and a flange 11 along its lower edge. Three chambers are thus formed, namely two outer or toasting chambers 12 and a central mechanism chamber or "chimney" 13 (Figure 3). Lying spaced from the reflecting sides of the plates 9 are four mica formers 14 carrying heating elements 15, 16, 17 and 18 connected in series (Figure 12), each toasting chamber 12 being thus bounded on two sides by two of the toasting elements respectively.

Each of the element formers is detachably held in position by two guard wires 19 each in the form of a U or hair-pin whose legs are undulated and whose apex or bend 20 is struck back to form a hook 21 adapted to engage in the corresponding slot 7 in the associated side strip 4 or intermediate tie 5, 6. Thus, the hooks 21 press the upper marginal portions of the formers 14 against the flutes 10 in the reflector plates 9, the lower extremities or prongs 22 of the guard wires 19 extending through apertures in the

flanges 11, with the lower edges of the formers 14 resting on the lateral extremities 22 at the lower ends of the guard wires 19 which bear against the lower marginal portions of the formers 14. In this way, the guard wires 19 serve not only as such but for detachably holding the reflector plates 9 and formers 14 in their operative positions.

The four ends of the foot strips 3 are secured to two blocks 23, 24 of insulating material which form the two feet of the toaster, one foot 23 carrying the terminals 24¹, 25, 26, 27, 28, 29 and 30 (Figures 2 and 12) of the electric power supply circuit energised through a flexible lead A, whilst the other foot 24 carries a base plate 31. A hood 32 formed of sheet metal fits over the metal frame, as shown in Figures 1, 2 and 3, and is furnished at its lower edge with inwardly directed lugs 33 whereby the hood 32 is secured to the two feet 23, 24. The upper surface of the hood 32 is provided with two elongated openings 34, which register respectively with the two toasting chambers 12, a clearance 35 being provided between the metal frame and the hood 32 all round so that air can flow not only up through the chimney 13 and thence out through the elongated slots 34, but also between the inner surface of the hood 32 and the non-reflecting surfaces of the outermost reflector plates 9, to the said slots. The hood 32 is thus always maintained at a temperature sufficiently low to allow handling without discomfort.

Arranged beneath the metal frame is a crumb tray 36 hinged at 37 and having a flange 38 for cooperating with a spring-loaded releasable stop 39. The crumb tray 36 is provided with a central elongated slot 40 so that cooling air can flow through the said slot 40 and upwards through the chimney 13 to be discharged through the slots 34. Secured by studs 41 to the lower surface of the crumb tray 36 is a table shield 42 having apertures 43 which register with the central slot 40 in the crumb tray 36. When, therefore, the pivoted crumb tray is in the closed position (as shown in Figures 1 and 3) air can flow upwards through the slots 43 in the table shield 42 and thence through the slot 40 in the crumb tray to the chimney 13, this vertical draught inducing an inward flow of air all round at 44 between the edge of the table shield 42 and the crumb tray 36. It will be seen from Figures 1 and 3 that the edges of the openings 40 as also the outer edges of the tray 36 are upwardly curved or deflected so as to tend to prevent crumbs being spilt from the tray and shield on to the table beneath. It will thus be apparent that in addition to the cooling of the hood 32 itself, as above described, the table or other supporting surface for the toaster is protected by the shield 42 against damage from radiant heat.

The hood 32 is provided on one side with a fixed handle 45 of heat-insulating material and on the other side with a central vertical slot 46 through which extends an operating lever 47 having secured to its outer end a handle 48 similar in appearance and of the same material as the fixed handle 45. The operating lever 47 is secured to a carrier plate 49 having integral lugs 50 rigidly connected respectively to two bread-carriers 51, 52 which extend longitudinally within the two toasting chambers 12 (Figure 2) the bread carriers 51, 52 being slidable through vertical slots 53 formed in the adjacent end wall 1 of the frame. The carrier plate 49 is also connected through vertically spaced pivots 54 to the adjacent ends 75 of

of two links 55, 56 which extend one above the other (Figure 1) through vertical slots 57, 58, 59 formed in the walls 1 and 2 at opposite sides of the chimney 13, the links 55 and 56 being connected to the wall 2 by spaced fixed pivots 60, 61. Mounted to turn about the fixed pivot 61 is a crank 62 connected through a loading spring 63 to a lug 64¹ on the end wall 1, the crank 62 carrying a loading arm 64 which extends through the chimney 13 so as to emerge through the vertical slot 57 beneath the carrier plate 49. Thus, when the operating handle 48 is pressed down, the two links 55 and 56 are turned about their pivots 60 and 61 against the action of the loading arm 64, the bread-carriers 51 and 52 simultaneously moving downwards within the toasting chambers 12.

The loading arm 64 normally holds the carrier plate 49 and the two bread carriers 51, 52 in their raised positions shown in Figure 1, but it should be noted that since the carrier plate 49 merely rests upon the loading arm 64, these two parts are independently movable vertically. When the carrier plate 49 is in its fully raised position it bears against two leaf springs 65, 66 secured to the end wall 1 and acting as resilient dampers to prevent shock when the carrier plate 49, after being released as described below, is raised from its lower or toasting position to its upper or delivery position. If desired a dash pot may be employed instead of the buffer springs 65, 66.

That end of the loading arm 64 adjacent to the carrier plate 49 is provided with an elbow 67, 68 (Figure 5) having an insulating strip 69 carrying a spring strip 70 supporting two bridging contacts 71, 72 electrically connected together but insulated from the elbow 67, 68 by the strip 69, the part 68 having a horizontal reset-control pin 73.

Mounted on the base plate 31 is a vertical pivot 74 (Figures 6 and 7) about which can turn a bracket 75 connected by a stud 76 to a stop arm 77 and which carries a horizontal pivot 78 for a bimetallic strip 79, the stop arm 77, bracket 75 and bimetallic strip 79 together forming a hairpin like unit as viewed in Figure 7. Extending around the pivot 74 is a coiled biasing spring 80 which tends to turn the stop arm 77 towards a face cam 81. The stop arm 77 cooperates with the end of a normally fixed basic stop 82 carried by a vertical portion 83¹ of a mechanism plate 83 mounted on the base plate 31, the stud 82 extending freely through a notch in the upper edge of the bimetallic strip 79. The free end of the stop arm 77 lies between, and cooperates with, the fixed basic stop 82 and the time adjusting stop constituted by the face cam 81 which is rotatable in a vertical lug 84 of the base plate 31, the spindle 85 of the cam 81 extending freely through an opening in the hood 32 to an adjusting knob 86 having an index or scale 87 for cooperating with a scale or index on the hood 32. The bimetallic strip 79 has an elongated slot 87¹ through which extends a stop rod 88 carried between the lug 84 and a flange 89 on the base plate 31, the rod 88 thus limiting movement of the strip 79 about the pivot 78. The bimetallic strip 79 carries a subsidiary electric heating element 90 secured to the bimetallic strip by metal straps 91, and the mechanism plate 83 has a horizontal portion 92 which supports the two contacts 93, 94 of a main switch for controlling the power supply circuit, the contacts 93, 94 cooperating with the bridging contacts 71, 72 on the loading arm 64 described above. The horizontal portion 92 of the mechanism plate 83 also supports a bifurcated plate 95 whose tines carry two fixed contacts 96, 97. Two movable contacts 98, 99 car-

ried by leaf springs 100 cooperate with the fixed contacts 96, 97, the contacts 98, 99 being mutually insulated by mica strips 101. The contacts 97, 99 constitute an auxiliary switch in series with the contacts 93, 94 of the main switch, and the contacts 96, 98 constitute a subsidiary switch for short-circuiting the subsidiary heating element 90 associated with the bimetallic strip 79.

Mounted to turn on a horizontal pivot 102 carried by the mechanism plate 33 is a latch 103 whose free end 104 is normally urged upwards towards a fixed stop 105¹ by a spring 106, the latch 103 being engaged and turned downwards by the adjacent end 107 of the loading arm 64 when the operating handle 48 is pressed downwards in order to lower the bread carriers 51, 52 into the toasting position. The latch 103 is thus mounted independently of the loading arm 64. The free end 104 of the latch 103 cooperates with a detent 105 (Figure 9) mounted to pivot at 106¹ against a coil spring 107 on a vertical bifurcated guide lug 108 carried by the base plate 31, the lower end 109 of the detent 105 being held by its spring 107 against a flat on the projecting end of a horizontal pivot pin 110 interconnecting a crank 111 on the bifurcated lug 108 and a stepped latch-control lever 112 which lies in a vertical slot 113 formed in the bimetallic strip 79 near the free end thereof. The latch-control lever 112 carries a stepped edge cam 114 of insulating material whose lower level 115 and higher level 116 respectively cooperate with the free ends of the two leaf springs 100 carrying the movable contacts 98 and 99.

A bell-crank lever 117 having one arm 118 pivoted on a horizontal pivot 119 on an upturned lug 120 of the base plate 31 is biased by a spring 121 so that its free arm 122 tends to move towards the adjacent end of the bimetallic strip 79. A pin 123 formed integrally with the pivot 119 extends through an elongated aperture 117¹ in the bell-crank lever 117 and tends to move towards the wider end 124 of the latch-control lever 112. A resetting lever, in the form of a curved wire 125, is pivotally connected to the base plate 31 at 126 and has a crank 127 lying beneath the latch-control lever 112, the upper or free end of the resetting lever 125 being curved at 125¹ so as to lie in the path of movement of the reset control pin 73. The bifurcated lug 108 has a lateral stop 108¹ which cooperates with a pivoted trip-control elbow 128 (Figures 1 and 2) having a transverse end portion 129 for cooperation with a spring-loaded manual trip button 130 carried by the hood 32. The elbow 128, when operated by the trip button 130, engages a lateral pin 131 on the detent 105 so as to move this out of engagement with the latch 103.

In the inoperative or cold condition of the toaster, the loading spring 63 holds the loading arm 64 in its raised position so that the said arm, in turn, holds the carrier plate 49 and toast carriers 51, 52 in their uppermost or delivery positions within the toasting chambers 12 as shown in Figure 1. The latch 103 is now held by its control spring 106 against the associated fixed stop 105¹ whilst the trip-control elbow 128 rests, by gravity, against the fixed stop 108¹. Since the lower edge 133 of the stepped latch-control lever 112 is bearing against the edge of the bimetallic strip 79 within the slot 113 thereof, the end of the lever 112 is raised sufficiently to cause the higher part 116 of the edge cam 114 to lift the moving contact 98 clear of its fixed contact 96, whilst the lower part 115 of the edge cam 114 lies beneath and clear of the spring strip 100 carrying the 75

moving contact 99 of the auxiliary switch, whereby the latter remains closed as shown in Figure 9. Thus, though the contacts 97, 99 of the auxiliary switch remain closed, power is not supplied to the heating elements 15—18 since the bridging contacts 71, 72 on the loading arm 64 lie well above and clear of the fixed contacts 93, 94 of the main switch as shown in Figure 1.

Having inserted one or two pieces of bread through the slot or slots 34 so as to rest on the bread carriers 51, 52 respectively, the operating handle 48 is pressed down against the action of the loading spring 63. As the loading arm 64 moves down, the lateral reset-control pin 73 thereon engages the curved upper end of the resetting lever 125 so as to turn this about its pivot 126 in the clockwise direction as viewed in Figure 9. The cranked portion 127 of the resetting lever 125 thus moves upwards against the lower edge 133¹ of the lever 112 so that the latter is raised and lifts the contact 99 to open the contacts 97, 99 as shown in Figure 11. As the reset-control pin 73 moves downwards beyond the curved part 125¹ of the resetting lever 125, this lever drops back in the counter-clockwise direction and allows the lever 112 to fall thereby reclosing the contacts 97, 99 just before the bridging contacts 71, 72 close the contacts 93, 94 of the main switch. The supply circuit to the heating elements 15—18, including the subsidiary element 90 associated with the bimetallic strip 79, is thus established. Just prior to closing the main contacts 93, 94, the end 107 of the loading arm 64 engages the pivoted latch 103 (as indicated in Figure 7) which is thus turned, against the action of its associated spring 106, until the free end 104 of the latch 103, guided by the fork at the upper end of the bifurcated guide lug 108, snaps into engagement beneath the detent 105, a claw 132 at the other end of the latch 103 simultaneously moving so as to lie over the loading arm 64 which is thus locked in its lowered position as shown in Figure 7.

If the cam 81 has been set for the shortest toasting period, there will be no gap between the cam 81 and the stop arm 77 of the bimetallic strip 79. Under these conditions, when the lever 47 has been lowered and the loading arm 64 latched so that the main contacts 93, 94 and the auxiliary contacts 97, 99 are closed and the subsidiary or short-circuiting contacts 96, 98 are open, current will flow through all the heating elements 15—18 and 90. There will now be a preliminary period during which initial stress is taken up in the bimetallic strip 79 which will not, therefore, as yet, move along the lower edge 133 of the latch-control lever 112. When this preload has been overcome, the free end of the bimetallic strip 79 will commence to move along the lower edge 133 towards the step 134 therein. As the bimetallic strip 79 moves, it is followed by the associated arm 122 of the bell-crank lever 117 which, however, will be arrested as soon as the bimetallic strip 79 is moved near enough to the step 134 for the pin 123 to abut against the free end 124 of the lever 112 as shown in Figure 10. The bimetallic strip 79 now reaches the step 134 in the lever 112 which therefore drops so that the short-circuiting contacts 96, 98 are closed and the heating element 90 of the bimetallic strip 79 is deenergised, thereby terminating the heating stage of the automatic timing cycle. After a slight continued flexure of the bimetallic strip 79, the cooling part of the cycle commences, i. e. the strip 79 commences to return, to the left as

viewed in Figures 9 to 11, and thus engages the step 134 in the lever 112 which is thereby drawn to the left to turn the detent 105 in the clockwise direction about its pivot 106. When the temperature of the strip 79 has fallen to the automatic tripping value, the strip reaches the automatic trip position corresponding to the end of the cooling part of the cycle and brings the detent 105 into a position in which it releases the latch 103 so that the free end 104 thereof rises and the claw 132 releases the loading arm 64 which therefore rises under the action of the loading spring 63 to lift the loading arm 64, carriers 51, 52 and toasted slices from the toasting position to the delivery position. As the loading arm 64 rises, the bridging contacts 71, 72 first open the main contacts 93, 94 to deenergise the toasting elements 15-18 whereupon the lateral reset-control pin 73 engages beneath the curved part 125¹ of the resetting lever 125 which is turned in the clockwise direction so that the crank 127 thereof lifts the lever 112 thereby opening both the short-circuiting contacts 96, 98 and the auxiliary contacts 97, 99. The pivoted detent 105 is now returned, by its control spring 107, to its initial position thus restoring the lever 112 to the position shown in Figure 9. With continued upward movement of the loading arm 64, the lateral reset-control pin 73 passes over the curved part 125¹ of the resetting lever 125 which therefore drops back and permits the lever 112 to be re-lowered until its edge 133 again rests on the edge of the bimetallic strip 79 within the slot 113. The auxiliary contacts 97, 99 are thus reclosed though the main contacts 93, 94 and the short-circuiting contacts 96, 98 remain open, the latter by reason of the associated contact strip 109 resting on the higher portion 116 of the edge-cam 114 (Figure 10). In this respect it should be noted that neither the auxiliary contacts 97, 99 nor the short-circuiting contacts 96, 98 at any time function to open the power circuit under load since this is carried out solely by the main contacts 71, 72 and 93, 94 always opening before the auxiliary contacts 97, 99 are opened.

As the loading arm 64 and carrier plate 49 approach their uppermost positions, i. e. to deliver the toasted slices through the slots 34, the carrier plate 49 bears against the damping springs 65, 66 thus reducing the tendency for sudden arrest of, and shock to, the upwardly moving parts, and preventing over-vigorous upward delivery of the toast.

The first timing cycle thus consists of three stages, namely a preliminary stage during which the preload on the bimetallic strip 79 is overcome, a heating stage during which the bimetallic strip 79 moves up to the step 134 in the latch-control lever 112, and a cooling stage during which the temperature of the bimetallic strip 79 drops to the automatic tripping value and thus moves the lever 112 back to the trip position. Both the heating and cooling stages take place exponentially, the automatic tripping temperature of the bimetallic strip 79 being somewhat higher than that at which the immediately initial heating stage commenced. Thus, if two further slices of bread are at once inserted and the operating handle 48 again depressed, the heating stage of the second timing cycle will commence at a temperature above that at the commencement of the immediately preceding heating stage. Clearly, since the parts have not been allowed to cool down, there is no preload to be overcome and the second timing cycle will con-

sist of two stages only, namely a heating stage somewhat shorter than the heating stage of the first cycle followed by a cooling stage, substantially the same as the cooling stage of the first cycle, which brings the bimetallic strip 79 back to the trip position. If, after the second cycle has been completed and the toast delivered, the toaster is again charged with bread and the load arm 64 pressed down, the third timing cycle will take place over a period slightly shorter than the second.

If, with the previous setting of the cam 81 the toast delivered is not sufficiently browned, the cam 81 is adjusted by the operator so as to provide a clearance X (Figure 7) between the cam and the stop arm 77. If now toasting is again to commence from cold and the toaster is charged as described above, there will again be a preliminary stage during which the bimetallic strip 79 does not move, but takes up the preload or initial stress. Even after cancelling this preload, however, the bimetallic strip 79 will still not move along the lever 112 since there is some slight frictional load between the strip 79 and lever 112 whereas the stop arm 77 is free to move towards the cam 81. The bimetallic strip 79 still remains stationary, therefore, until the stop arm 77 has crossed the gap X and bears against the cam 81, whereupon the bimetallic strip 79 commences to move along the edge 133 of the lever 112. The duration of the heating stage of the first timing cycle is thus increased by reason of the gap X which has to be taken up between the stop arm 77 and the cam 81. At the end of the heating stage of this first cycle the bimetallic strip 79 again reaches the step 134 in the lever 112 which is thus moved down to close the short-circuiting contacts 96, 98 and thus to deenergise the heating element 90. As a result, the bimetallic strip 79 commences to cool, but the strip 79 itself will not move since there is some frictional load thereon whereas the stop arm 77 can move away from the cam 81 through the distance between the arm 77 and the basic stop 82. As the bimetallic strip 79 cools down, therefore, the arm 77 thereof will first move away from the cam 81 until the arm 77 abuts against the basic stop 82 whereupon the strip 79 itself will move back, engage the step 134 in the latch control lever 112 and, having moved this to the left as viewed in Figures 9 to 11, will release the detent 105 and trip the mechanism when the temperature of the bimetallic strip 79 has fallen to the automatic tripping value as before. It will be apparent that the larger the gap X between the stop arm 77 and the cam 81, that is to say the higher the time setting on the adjusting knob 36, the longer will be the timing cycle including the heating stage plus the succeeding cooling stage. As before, if two further pieces of bread are inserted in the toaster and the operating handle 48 again pressed down, the heating part of the second cycle will commence when the temperature of the bimetallic strip 79 is somewhat above that at the commencement of the heating stage of the first cycle.

If, during an automatic timing cycle (but after the preliminary heating part of a first cycle) the operator raises the operating handle 48 to examine the toast and finds this already either to his liking or over-toasted, he presses the manual trip button 130 so that the associated trip-control elbow 128 engages the pin 131 on the detent 105 and releases the latch 103. As the loading arm 64 rises and thus opens the main contacts 93, 94,

the resulting movement of the resetting lever 125 raises the lever 112 and thus opens both the auxiliary contacts 97, 99 and the short-circuiting contacts 96, 98. Since the free end of the bimetallic strip 79 is now spaced away from the cooperating arm 122 of the associated bell-crank lever 117, and the free end 124 of the lever 112 is raised above the level of the pin 123 on the bell-crank lever 117, this lever will turn until the pin 123 lies under the free end of the latch control lever 112 i. e. against the edge 133. When, therefore, the loading arm 64 rises to its uppermost or delivery position, though the resetting lever 125 drops back, return of the latch-control lever 112 is prevented by the pin 123 of the bell-crank lever 117. Thus, the auxiliary contacts 97, 99 will be maintained open so that even if the toaster is immediately recharged and the operating handle 48 pressed down to close the main contacts 93, 94 and relatch the loading arm 64, the power circuit will remain open at the auxiliary contacts 97, 99. The next toasting cycle cannot therefore begin until the bimetallic strip 79 has cooled down to the automatic tripping temperature, that is to say until the strip 79 has moved back to engage the arm 122 of the bell-crank lever 117 and thus to move the pin 123 out from beneath the lever 112 which then drops down, thus closing the auxiliary contacts 97, 99 but leaving the short-circuiting contacts 96, 98 open. The arrangement is such that the lever 112 is released by the pin 123 when the temperature of the bimetallic strip 79 has fallen to the automatic tripping value and the bimetallic strip 79 has reached the tripping position.

It will be apparent, therefore, that though the toaster has been tripped at random and during a timing cycle, immediate recharging and relatching of the toaster will not result in the remainder of that cycle being applied to the next slices, with consequent under-toasting, since the next cycle cannot commence until the bimetallic strip 79 has moved back to the automatic tripping position whereupon the next timing cycle will commence automatically.

In the event of the toast as delivered when the toaster is tripped automatically at the end of a complete timing cycle being insufficiently browned, the operator merely presses down the operating handle 48 again so that the next cycle commences at the beginning of a heating stage and, after applying an additional toasting period to the bread (which may be checked by raising the handle 48 and carriers 51, 52) the operator presses the manual trip button 130. Here again, the toaster can be immediately recharged without risk of a shortened cycle being thereupon applied to the bread since the manual trip has, as above described, left the latch-control lever 112 in the raised position with the auxiliary contacts 97, 99 open so that the next timing cycle can only commence when the bimetallic strip 79 has returned to the normal trip position.

It will be apparent that the operator, having found that with the timing cycle as set by the cam 81 the bread is undertasted or overtoasted at the termination of a cycle, or begins to smoke before such termination, will adjust the said cam to rectify the next succeeding cycle. Whatever his setting, however, he is not committed thereto since, after manually raising the carriers 51, 52 (without disturbing the timing cycle in progress) if toasting is already adequate, he can manually trip the mechanism, reset the cam 81 to give a second and shorter toasting period and

recharge the toaster without risk that only the residue of the first timing cycle will be applied to the newly inserted slices. Similarly, should the slices delivered at the termination of an automatically timed cycle be undertasted, the operator need only press the handle 48 down again for a partial cycle until the toast is done to his liking whereupon he manually trips the mechanism to effect delivery, again without prejudicing a full cycle, as set, for the next slices of bread inserted.

It will be understood that the construction described above is given by way of example only and that details may be modified to suit requirements.

What we claim as our invention and desire to secure by Letters Patent is:

1. An electric toaster comprising at least two supports mutually spaced to provide a toasting space between them, electric toasting elements carried by the supports, a bread carrier disposed within said space, a loading spring biasing the carrier from a toasting position towards a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature-responsive device associated with the subsidiary heating element, a subsidiary switch controlling the energisation of the subsidiary element, a latch-control member actuated by said temperature-responsive device and operatively connected to the latch, subsidiary switch and auxiliary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, and locking means cooperating with the latch-control member, manual tripping of the latch causing said locking means to engage and lock the latch-control member in a position in which it retains the auxiliary switch open until the temperature-responsive device, on its return to the automatic tripping position, engages and moves the locking means out of engagement with the control member.
2. An electric toaster comprising at least two supports, mutually spaced to provide a toasting space between them, electric toasting elements carried by the supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature-responsive device associated with the subsidiary heating element, a subsidiary switch controlling the energisation of the subsidiary element, a latch-control member actuated by said temperature-responsive device and operatively connected to the latch, subsidiary switch and auxiliary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, and locking means cooperating with the latch-control member, manual tripping of the latch causing said locking means to engage and lock the latch-control member in a position in which it retains the auxiliary switch open until the temperature-responsive device, on its return to the automatic tripping position, engages and moves the locking means out of engagement with the control member.

3. An electric toaster comprising at least two supports, mutually spaced to provide a toasting space between them, electric toasting elements carried by the supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature-responsive device associated with the subsidiary heating element, a subsidiary switch controlling the energisation of the subsidiary element, a latch-control member actuated by said temperature-responsive device and operatively connected to the latch, subsidiary switch and auxiliary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, and locking means cooperating with the latch-control member, manual tripping of the latch causing said locking means to engage and lock the latch-control member in a position in which it retains the auxiliary switch open until the temperature-responsive device, on its return to the automatic tripping position, engages and moves the locking means out of engagement with the control member.
4. An electric toaster comprising at least two supports, mutually spaced to provide a toasting space between them, electric toasting elements carried by the supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature-responsive device associated with the subsidiary heating element, a subsidiary switch controlling the energisation of the subsidiary element, a latch-control member actuated by said temperature-responsive device and operatively connected to the latch, subsidiary switch and auxiliary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, and locking means cooperating with the latch-control member, manual tripping of the latch causing said locking means to engage and lock the latch-control member in a position in which it retains the auxiliary switch open until the temperature-responsive device, on its return to the automatic tripping position, engages and moves the locking means out of engagement with the control member.

gisation of the subsidiary element, latch-control means actuated by said temperature-responsive device and operatively connected to the latch, auxiliary switch and subsidiary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, and locking means cooperating with the latch-control means and which, after manual tripping of the latch, holds the auxiliary switch open unless and until the temperature of the temperature-responsive device does not exceed that corresponding to the said automatic tripping position of the temperature-responsive device.

3. An electric toaster comprising at least two supports mutually spaced to provide a toasting space between them, electric toasting elements carried by said supports, a bread carrier disposed within said space, a loading spring biasing the carrier from a toasting position towards a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, a subsidiary heating element, a temperature-responsive device associated with the subsidiary heating element, a subsidiary switch controlling the energisation of the subsidiary element, the subsidiary switch, when closed, short-circuiting the subsidiary element, an auxiliary switch controlling the continuity of said toaster circuit, a latch-control member actuated by said temperature-responsive device and operatively connected to the latch and to the subsidiary and auxiliary switches, cocking of said spring closing the main switch and engaging said latch whereupon the temperature-responsive device, after a predetermined response, closes the subsidiary switch to deenergise the subsidiary heating element, the temperature-responsive device, on cooling, returning to an automatic tripping position wherein it trips the latch so that the spring moves the carrier to the delivery position, a resetting device associated with the latch-control member, means operated by said spring and engaging the resetting device whereby, when said latch is released, the resetting device is actuated and moves the latch control member to open both the subsidiary and auxiliary switches, a manually operable tripping device associated with said latch, and locking means operatively associated with the temperature-responsive device and latch-control member, manual tripping of the latch thus causing the main, auxiliary and subsidiary switches to be opened whereupon recocking of the spring to reengage the latch recloses the main switch whereas the latch-control member is held by the locking means in a position in which it prevents reclosing of the auxiliary switch until the temperature-responsive device returns to a position in which it engages and moves the locking means out of engagement with the latch-control member.

4. An electric toaster comprising at least two supports mutually spaced to provide a toasting

space between them, electric toasting elements carried by said supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature responsive device associated with the subsidiary heating element, a subsidiary switch controlling the energisation of the subsidiary element, a pivoted latch-control member actuated by said temperature-responsive device and operatively connected to the latch, subsidiary switch and auxiliary switch, cocking of said spring closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position thereby opening the main switch, a resetting member cooperating with the latch-control member, means operatively connected to said spring and cooperating with the resetting member, automatic tripping of said latch thus causing said spring to act through the resetting member on the latch-control member which is turned about its pivot to open the subsidiary switch and to open and reclose the auxiliary switch, recocking of the spring turning said latch-control member to open and reclose the auxiliary switch and closing the main switch, a manually operable tripping device associated with the latch, and locking means cooperating with the temperature-responsive device and latch control member, manual tripping of the latch causing said locking means to engage and lock the control member in a position in which it retains the auxiliary switch open until the temperature-responsive device, on its return to the automatic tripping position, engages and moves the locking means out of engagement with the latch-control member.

5. An electric toaster comprising at least two supports mutually spaced to provide a toasting space between them, electric toasting elements carried by said supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling the continuity of said toaster circuit, a subsidiary heating element, a temperature responsive device associated with the subsidiary heating element, a subsidiary switch controlling the energisation of the subsidiary element, latch-control means actuated by said temperature-responsive device and operatively connected to the latch, subsidiary switch and auxiliary switch, cocking of said spring closing the main switch and engaging said latch whereupon the temperature-responsive device, after a predetermined response, operates the subsidiary switch to deenergize the subsidiary

13

heating element, the temperature-responsive device, on cooling, returning to an automatic tripping position wherein it trips the latch, a reset member associated with said latch-control means, means operatively connected to said loading spring and cooperating with the reset member, so that when the latch is tripped the spring moves the carrier to the delivery position, opens the main switch and then acts through the reset member on the latch-control means to open the auxiliary switch, a manually operable tripping device associated with the latch, and locking means cooperating with the temperature-responsive device and latch control member, manual tripping of the latch causing said locking means to engage and lock the latch-control member in a position in which it retains the auxiliary switch open until the temperature-responsive device, on its return to the automatic tripping position engages and moves the locking means out of engagement with the latch-control member.

6. An electric toaster comprising at least two supports mutually spaced apart to provide a toasting space between them, electric toasting elements carried by the supports, a bread carrier disposed within said space, a loading spring biasing the carrier from a toasting position towards a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, a subsidiary heating element, a temperature-responsive device associated with the subsidiary heating element, a subsidiary switch controlling the energisation of the subsidiary element, the subsidiary switch when closed, short-circuiting the subsidiary element, an auxiliary switch controlling the continuity of said toaster circuit, a latch-control member actuated by said temperature-responsive device and operatively connected to the latch and to the subsidiary and auxiliary switches, cocking of said spring closing the main switch and engaging said latch whereupon the temperature-responsive device, after a predetermined response, closes the subsidiary switch to deenergise the subsidiary heating element, the temperature-responsive device, on cooling, returning to an automatic tripping position wherein it trips the latch, so that the spring moves the carrier to the delivery position, a resetting device associated with the latch-control member, means operated by said spring whereby, when said latch is released, the resetting device is actuated and moves the latch-control member to open both the subsidiary and auxiliary switches, a manually operable tripping device associated with said latch, and locking means associated with the temperature-responsive device and latch-control member, manual tripping of the latch thus causing the main, auxiliary and subsidiary switches to be opened whereupon recocking of the spring to reengage the latch recloses the main switch whereas the latch-control member is held by the locking means in a position in which it prevents reclosing of the auxiliary switch until the temperature-responsive element returns to a position in which it engages and moves the locking means out of engagement with the latch-control member.

7. An electric toaster comprising at least two supports mutually spaced to provide a toasting space between them, electric toasting elements carried by the supports, a bread carrier disposed

14

within said space, a manually operable handle extending from the carrier, a pivoted loading arm arranged within the toasting space, said carrier resting on the loading arm, a loading spring biasing said arm towards the carrier thus tending to move the carrier from a toasting position towards a delivery position, a main switch controlling the continuity of the toaster circuit which includes said toasting elements, means whereby said main switch is closed by the cocking of said spring, a pivoted latch carried by the base, a spring biasing said latch, a pivoted lever cooperating with the latch, a spring biasing the lever towards the loading arm, a retaining lug carried by said lever and cooperating with the loading arm, an auxiliary fixed contact carried by the base, an auxiliary movable contact cooperating with the auxiliary fixed contact to control the continuity of the said toaster circuit, a subsidiary heating element in series with the toasting elements, a bimetallic strip associated with the subsidiary heating element, a subsidiary fixed contact carried by the base, a subsidiary movable contact cooperating with the subsidiary fixed contact to short-circuit the subsidiary heating element, a stepped latch control member pivotally connected to said latch, a reset lever mounted to pivot on said base, a crank carried by said reset lever and lying beneath the latch control lever, a reset pin carried by the loading arm and cooperating with the reset lever, a switch-actuating member carried by the latch-control lever and cooperating with said auxiliary and subsidiary movable contacts, a manually operable trip lever carried by the base and cooperating with said latch, a pivoted stop lever carried by the base and operatively connected to said bimetallic strip, a cam cooperating with said stop lever, means for adjusting the cam to determine the spacing between the cam and the stop lever, locking means comprising a bell-crank lever, a pivot connecting one arm of said bell-crank lever to the base, a spring biasing the other arm of the bell-crank lever into contact with the bimetallic strip, and an abutment carried by said bell-crank lever and cooperating with the lower edge of said latch-control member, manual tripping of said latch causing the reset pin to turn the latch-control member thus opening the auxiliary contacts and raising the lower edge of the latch-control member above the level of said abutment which thus moves so as to lie beneath the said lower edge thereby preventing reclosing of the auxiliary contacts until the bimetallic strip, on cooling, engages the bell-crank lever to move the abutment out of engagement with the latch-control lever.

8. An electric toaster as claimed in claim 1, having means whereby tripping of the latch, whether automatic or manual, causes the main switch to open before opening of the auxiliary switch so that opening of the toaster circuit under load is effected solely by the main switch.

9. An electric toaster comprising at least two supports mutually spaced to provide a toasting space between them, electric toasting elements carried by the supports, a bread carrier disposed within said space, a loading spring biasing the carrier from a toasting position to a delivery position, a main switch controlling the continuity of the toaster circuit which includes said toasting elements, means whereby said main switch is closed by the cocking of said spring, a latch, means operatively connected to the spring and engaged by the latch to retain the spring in its cocked condition, an auxiliary switch controlling

the continuity of said toaster circuit, a subsidiary heating element, a temperature-responsive device associated with the subsidiary heating element, a subsidiary switch controlling the energisation of the subsidiary element, a latch-control member actuated by said temperature-responsive device and operatively connected to the latch, subsidiary switch and auxiliary switch, cocking of said spring thus closing the main switch and engaging said latch whereupon the temperature-responsive device, after a predetermined response, operates the subsidiary switch to deenergise the subsidiary heating element, the temperature-responsive device, on cooling, returning to an automatic tripping position wherein it trips the latch so that the spring moves the carrier to the delivery position and opens the main switch, a manually operable tripping device associated with the latch, a locking device, a spring biassing the locking device into contact with said temperature responsive device, an abutment carried by the locking device and cooperating with the latch control member, the locking device moving with the temperature-responsive device until the abutment engages the latch control member and arrests further movement of the locking device, a resetting member associated with the latch-control member, and means operatively connected to the loading spring and actuating said resetting member whereby the latch control means is moved relatively to said abutment when the latch is tripped, manual tripping of the latch thus causing said abutment to lock the latch control member in a position corresponding to the open position of the auxiliary switch until the temperature-responsive device returns to the automatic tripping position wherein the temperature-responsive device reengages the locking device and moves said abutment out of locking engagement with the latch-control member.

10. An electric toaster comprising at least two supports, mutually spaced to provide a toasting space between them, electric toasting elements carried by the supports, a bread carrier disposed within said space, a loading spring biassing the carrier from a toasting position towards a delivery position, a main switch controlling the continuity of the toaster circuit which includes said toasting elements, means whereby said main switch is closed by the cocking of said spring, a latch, means operatively connected to the spring and engaged by the latch to retain the spring in

its cocked condition, a subsidiary heating element, a temperature-responsive device associated with the subsidiary heating element, a subsidiary switch controlling the energization of the subsidiary element, latch-control means actuated by said temperature-responsive device and operatively connected to the latch and subsidiary switch, cocking of said spring thus closing the main switch and engaging said latch whereupon the temperature-responsive device, after a predetermined response, operates the subsidiary switch to de-energize the subsidiary heating element, the temperature-responsive device, on cooling to a predetermined temperature, returning to an automatic tripping position in which it trips the latch, a manually operable device for tripping said latch while said temperature-responsive means is above said predetermined temperature, an auxiliary switch in series with said main switch, means operating upon tripping of said latch to open said auxiliary switch, and locking means responsive to movement of said temperature-responsive means to prevent reclosure of said auxiliary switch while said temperature-responsive device is above said predetermined temperature, said temperature-responsive device carrying a stop arm lying between, and cooperating with, a normally fixed basic stop and a time adjusting stop, initial movement of the temperature-responsive device at the beginning of the timing cycle and at the beginning of the cooling stage thereof being delayed in accordance with the lost motion available between the stop arm and the adjustable and fixed stops.
